14 Claims. (Cl. 199—51)

The present invention relates to improvements in typographical machines and more especially to those of the well-known class as generally shown and described in U. S. Letters Patent No. 436,532 granted September 16, 1890, wherein character bearing matrices and expansible spacebands are assembled in lines which are introduced between the jaws of a vise, the lines are justified by expansion of the spacebands therein, and type bars or slugs are cast from the lines, after which the matrices are distributed and returned to a magazine from which they were drawn and the spacebands returned to their place of storage, and the invention relates more particularly to developments of machines of this class having means for quadding at either end of a matrix line by closing one or the other vise jaw against the respective end of the line and for centering the line by closing both jaws against the ends of the line.

In machines of this class, the spacebands are justified ordinarily in two operations, the first of which spreads the line endwise to take up looseness therein by expanding the well-known slidable wedge spacebands, and the second of which operations finally tightens the line immediately prior to the casting of the type bar or slug therefrom. The first justification is effected customarily by advancing the so-called justification bar upwardly against the depending spaceband wedges, the bar, during this operation, being inclined downwardly toward the left end of the matrix line so as to engage the spaceband wedges successively from right to left, thus allowing each successive spaceband to creep along the justification bar naturally in the direction in which its upper end, together with the matrices, is moved, due to progressive expansion of the line from right to left.

Such justification is satisfactory when it is only required that all matrix lines be spread or justified from right to left, which is usual when justifying full lines, but when the machine is arranged to quad out lines composed to less than full measure for which the machine is set, by moving one or the other or both vise jaws, a new condition arises which makes it impracticable to justify lines always with the justification bar inclined in the same direction. Since the right hand vise jaw in the machine normally stands in a definite position known as line receiving position and all matrix lines are delivered between the jaws with the matrix at the right hand end thereof alined vertically with the face of this jaw, if this jaw is moved to the left to quad out the right hand end

of a line, as for example a short line at the end of a paragraph, the line of matrices is also moved to the left until its left hand end contacts with the face of the left hand vise jaw, but since the left hand jaw is held against a stop in the machine to fix the left hand end or beginning of the line in column alinement with other lines, any spreading due to justification of the matrix line must take place toward the right. Similarly, the left hand jaw in the machine may be arranged to quad out the left end of a matrix line, as for example, the first line of a paragraph, to provide the usual paragraph indentation or to quad out at the beginning of lines intended to aline at the right margin of the printed page, in which case the right hand jaw remains stationary against a stop in the machine to fix the right hand end of the line, so that any spreading of the matrix line, due to justification, must take place toward the left. In machines adapted for quadding, the particular jaw which is moved inwardly against the matrix line to effect the quadding out of the unfilled portion of the line is capable of moving outwardly under the influence of expansion of the spacebands in the line to effect justification, and the spreading of the line during such expansion of the spacebands will be in a direction toward the movable jaw. Consequently, if justification is to spread a line to the right, then the justification bar should be inclined downwardly to the right to permit the natural creep of the spacebands in that direction, and if justification is to spread the matrix line to the left, then the justification bar should be inclined downwardly to the left for the same reason. Also, if a line is to be quadded out at both ends, as where the machine is arranged to move both vise jaws equidistantly toward one another to effect centering of the lines, then the justification bar need not be inclined in either direction but should be horizontal, since the spreading of the line will then take place both to the right and the left.

The primary object of the present invention is to provide practical and simple means for setting the justification bar in an appropriate position to effect justification satisfactorily and effectively according to whether a matrix line is being quadded out with either one or both of the vise jaws, the justification bar, according to the present invention, being so mounted and operated that it may be inclined downwardly either toward the right hand or the left hand vise jaw according to whether quadding is being done with the right hand or the left hand jaw, whereby the inclination of the justification bar will favor the creep

of the spacebands in the direction in which the line is spread during justification, thereby avoiding strain or bending of the spacebands when forced upwardly through the line, and the justification bar is capable of occupying a horizontal position when quadding or centering is being done with both vise jaws, thereby facilitating the creep of the spacebands toward both ends of the line.

A further object of the invention is to provide control means between the justification bar and the devices for selecting the vise jaw or jaws with which it is desired to quad, whereby the justification bar will be set automatically to incline downwardly toward the particular jaw selected for quadding movement, or the justification bar will be set automatically in horizontal position when the jaw selecting means is set for quadding or centering with both vise jaws.

To these and other ends the invention consists in certain improvements and combinations and arrangements of parts all as will be hereinafter more fully described, the features of novelty being pointed out more particularly in the claims at the end of this specification.

In the accompanying drawings:—

Figure 1 is a rear elevation of the vise and cooperative justifier embodying the present invention, the justifier being set to justify a line of matrices from left to right as viewed from the front of the machine;

Figure 2 is a view of a part of the structure shown in Figure 1, but showing the justifier set to justify a matrix line from right to left as viewed from the front of the machine;

Figure 3 is a view similar to Figure 2, but showing the justifier set to justify a matrix line toward both ends, as a line to be centered;

Figure 4 is a top plan view, partly in section, of the structure shown in Figure 1;

Figure 5 is an elevation of the structure shown in Figure 4 as viewed from the left hand side thereof;

Figure 6 is a transverse vertical section taken on the line 6—6 in Figure 4 and looking toward the left; and

Figure 7 is a detail vertical section taken on the line 7—7 of Figure 3.

Similar parts are designated by the same reference characters in the different figures.

The present invention is applicable to typographical machines having means of different forms for quadding or quadding and centering of matrix lines, the invention being shown in the present instance applied for example to quadding and centering means of the kind shown and described in the prior application of Samuel E. Sperry, Serial No. 612,349 filed May 19, 1932, 1 and 2 representing the right hand and left hand jaws of the vise in the machine, these jaws being guided to slide toward and from one another in the vise frame 3, and 4 represents a rack bar which is connected by a link 5 to an arm 6, the latter being pivoted at 7 and provided with an arm 8 which is connected by a spring 9 to a suitable operating part of the machine so that the arm 6 and its connected parts constitute a power operated device for closing either or both of the jaws against a matrix line M containing the usual wedge or expandible spacebands S after the same has been lowered into position between the vise jaws by the descent of the first elevator 10 in the manner usual in machines of this class. The rack bar 4 is adapted to be connected to and disconnected from the right hand jaw 1 by a pin 11 mounted to reciprocate in the block 12 carry-

ing the jaw 1, this pin, when moved in one direction engaging in an aperture 13 in the bar 4 and thereby connecting the latter to the jaw 1 so that said jaw will be operatively connected to the bar 4, and when the pin 11 is shifted in the opposite direction, it will be retracted from the aperture 13 in the bar 4, thereby disconnecting the latter from the jaw 1, and the pin will be engaged in a locking recess 14 formed in the vice frame 3, the jaw 1 being then locked in its normal or fully open position against its stop 15. The bolt 11 is shifted by a stud 16 projecting therefrom and engaging a lever 17, the latter being pivoted at 18 on the jaw block 12 and having an open fork 19 at one end to receive a pin 20 carried by a link 21, the latter being slidably mounted on the vice frame by a screw 22 engaging in a slot 23 in the link 21 and the link 21 being pivotally connected at 24 to an arm 25, the latter being fixed on a shaft 26 rotatably mounted in suitable bearings on the top of the vice frame. The shaft 26 has an operating handle or lever 27 fixed thereon whereby said shaft may be rotated into different positions, and the shaft 26 carries a pointer 28 arranged to operate with a suitably graduated scale 29 which appropriately indicates the different settings of the shaft 26. The shaft 26 also has an arm 30 fixed thereon, this arm carrying a pin 31 arranged to operate in a cam slot 32 formed in a lever 33, this lever being pivoted at 34 on the vice frame and carrying at its opposite end a pin 35 which is operatively connected to the upper end of a spindle 36 which is shiftable vertically in the vice frame and carries a rotatable pinion 37 at its lower end which is movable into and out of engagement with rack teeth on the rack bar 4 and rack teeth on a rack bar 38 fixed to the block 2^a which carries the left hand jaw 2, the cam slot 32 being of such shape that the pinion will mesh with both rack bars when the shaft 26 is set for quadding with the left hand jaw 2 and for centering and will be disengaged from said rack bars when said shaft is set for quadding with the right hand jaw 1. By the arrangement described, when the shaft 26 is rotated by the handle 27 to bring the pointer 28 opposite to the legend "L. H. Q.", the link 21 will be shifted in a direction to withdraw the pin 11 from the aperture 13 in the rack bar 4, thereby disconnecting the right hand jaw 1 therefrom and at the same time the arm 30 on the shaft 26 will operate in the cam slot 32 in the lever 33 to rock the latter in a direction to move the pinion spindle 36 downwardly, thereby engaging the pinion 37 with the rack bars 4 and 38, the parts being shown in this position in Figures 4, 5 and 6 and the device being then set for quadding with the left hand jaw 2 which is then connected to the actuating rack bar 4 through the pinion. When the shaft 26 is rotated by the handle 27 to bring the pointer 28 into register with the legend "Center" on the scale 29, the arm 25 will pull the link 21 in a direction to engage the pin 11 in the aperture 13 in the rack bar 4, thereby connecting this rack bar to the right hand jaw 1, and this rotation of the shaft 26 will, at the same time move the pin 31 on the arm 30 in the cam slot 32 in the lever 33, but this cam slot is of such a shape that the lever 33 will not be rocked by such movement of the pin 31 and hence the pinion 37 will remain in mesh with both rack bars 4 and 38, so that when the shaft 26 is set in this position, both jaws 1 and 2 will be connected to the rack bar 4 and its operating arm 6 and will move simultaneously for centering a matrix line. Rotation of the shaft 26 by the handle 27 to bring

- the pointer 28 into register with the legend "R. H. Q." on the scale 29, causes the arm 25 to impart further movement to the link 21 which merely moves the pin 11 further into the aperture 13 in the rack bar 4, this rack bar thus remaining in connected relation with the right hand jaw 1, but the arm 30 on the shaft 26 will move the pin 31 thereon into the inner end of the cam slot 32 in the lever 33 and will rock this lever in a direction to lift the pinion 37 out of mesh with the rack bars 4 and 38, the right hand jaw 1 being then connected to the rack bar 4 but the left hand jaw 2 being disconnected therefrom, the parts being then set for right hand quadding. 80
- 13 From the foregoing it will be understood that the jaw closing mechanism may be set for quadding with either the right hand or the left hand jaw, or for quadding or centering with both jaws, and it will be further understood that the portion or 85
- 20 portions of the mold cavity not closed by the matrix line will be closed by the quadding movement of the movable jaw or jaws. As in the prior application hereinbefore referred to, a locking pawl 39 pivotally connected to a lever 40 is operated by the justifier during its justifying strokes and is engageable with ratchet teeth 41 on the rack bar 4 to limit the extent of outward movement of the jaw or jaws under the expanding influence of the spacebands in the line during 90
- 30 justification thereof. 95
- The justifier comprises a justification bar 42, a justifier frame 43, rods 44 guided to move vertically in the vise frame, and the usual first and second justification levers 45 and 46 respectively. 100
- 35 The frame 43 is bored at its ends to rigidly receive the upper ends of the rods 44, which are rigidly secured in said frame by fastening pins 43^a, and the justification bar 42 is formed on its under side with a web 47 which fits movably into the frame 43 for which purpose the latter is hollowed out at the center as shown in Figure 7. The web 105
- 40 47 has a cross-pin 49 fixed therein which is movable in vertical slots 48 in the sides of the frame 43, said pin and slots permitting the justification 110
- 45 bar 42 to rest in a horizontal position on the top of the frame 43 as shown in Figure 3 or to be tilted into either of the inclined positions represented by the dotted lines in Figure 1 or as shown in Figure 2, the pin 49 however preventing displacement 115
- 50 of the justification bar from the frame 43. The web 47 on the justification bar is provided at opposite side of the pin 49 with projections 50 and 51, and a pin 52 extends through the frame 43 at a point between said projections on the web. The 120
- 55 brace bar 54 is pivotally connected at its lower end to a sleeve 55 which latter is slidable vertically on the respective rod 44 so that it will be raised and lowered by the first justification lever 45, and the upper end of the brace bar 54 is provided 125
- 60 with a fork 56 and is movable transversely and vertically in the hollow central portion 57 of the frame 43, so that the fork 56 may be set to engage one or the other of the projections 50 and 51 on the web 47 of the justification bar 42 or 130
- 65 may be set to engage the cross-pin 52 fixed in the frame 43. By this arrangement, when the cross-brace 54 is set to engage the projection 51 on the justification bar 42, ascent of the cross-brace under the action of the first justification 135
- 70 lever 45 will cause the justification bar to be tilted so that it is inclined downwardly toward the jaw 1, as shown in Figure 1, and when the brace bar 54 is set to engage the projection 50 on the justification bar 42, the latter will be tilted 140
- 75 so that it will incline downwardly toward the jaw 145
- 2, as shown in Figure 2, during justification. When the brace bar 54 is set in a position to engage the pin 52 fixed in the frame 43, the latter will be lifted while the justification bar rests horizontally thereon during justification, as shown in Figure 3. 150
- Since the brace bar 54 does not support the frame 43 in normal position, nor will this frame be supported by the sleeve 55 which is loose on the respective rod 44 instead of being pinned thereto as usual in machines of this class, stop pins 44^a are fixed in the rods 44 and arranged to seat on the vise frame 3 when the frame 43 is in its normal lowered position and thereby support said frame in normal position, as shown by the full lines in Fig. 1.
- The setting of the brace bar is preferably effected automatically by the setting of the handle 27 by the operator to quad with either jaw or to quad or center with both jaws, for which purpose a slide 58 is guided by a pin 59 operating in a slot 60 therein to move horizontally on the vise frame, this slide being provided with a guide 61 in which the upper end of the brace bar fits and is shiftable vertically, the slide 58 being pivotally connected to the lower arm of a bell crank lever 62 which is pivoted at 63 on the vise frame and the upper arm of which is pivotally connected to a rod 64, the latter being pivotally connected at its upper end to an arm 105
- 65 fixed on the shaft 26, these parts being so constructed and arranged that when the handle 27 is set for quadding with the right hand or the left hand jaw, the slide 58 will be shifted to bring the brace bar 54 into position to engage 110
- the projection 50 or the projection 51 on the justification bar 42 and when the handle 27 is set for quadding or centering with both jaws, the slide 58 will occupy an intermediate position and will set the brace bar 54 to engage the pin 52 in 115
- the frame 43. 120
- The operation is as follows:—In Figure 1, the full lines show the justification bar 42 in normal position as when the machine is idle. The dotted lines in this figure represent the position of the justification bar during the usual first justification of a line when the operator has set the handle 27 at the "RHQ" indication, whereby matrix lines set too short to justify to full column measure will be quadded out at the right 125
- hand end. Under such conditions, the connections 53, 62, 64 and 65 between the shaft 26 carrying the handle 27 and the brace bar 54 have set the brace bar in position to engage the projection 51 on the web 47 of the justification bar 130
42. Accordingly, when the first justification lever 45 is lifted in the usual way to move the justification bar upwardly, the brace bar 54 acting on the projection 51 thereon tilts or inclines the justification bar so that it inclines downwardly 135
- toward the right hand jaw 1, as indicated by the dotted lines in Figure 1, and at the same time, the brace bar 54 lifts or raises the frame 43 and rods 44 upwardly as a unit. Since the spread of the line is toward the right hand jaw 1 under 140
- the conditions described, such inclination of the justification bar is proper to allow the spacebands to creep naturally down the incline. 145
- Figure 2 represents the condition when the handle 27 has been set to the "LHQ" indication to quad out the left hand end of a line, in which case the connections 58, 62, 64 and 65 have swung the brace bar 54 so that its upper end is in position to engage the projection 50 on the web 47 of the justification bar 42. Accordingly, when first 150

justification occurs, the brace bar 54 will rise and act on the justification bar to incline it downwardly toward the left hand jaw 2 as shown in this figure, and this incline of the justification bar will be proper to allow a natural creep of the spacebands toward the jaw 2.

Figure 3 represents the condition when the handle 27 has been set at the "Center" indication, in which case there will be an equal spread 10 of the line in both directions during justification. Under this condition, the connections 58, 62, 64 and 65 have brought the upper end of the brace bar 54 into position to engage the pin 52 rigid in the frame 43, and hence, when first justification 15 occurs, the brace bar 54 will engage this pin rather than the web 47 of the justification bar, so that the justification bar will merely rest in horizontal position on the frame 43 and the lifting of this frame by the rise of the brace 20 bar 54 will therefore carry the justification bar upwardly while occupying the horizontal position shown in Figure 3 and allowing a natural creep of the spacebands toward both of the jaws.

In respect to operation of the justifying means 25 during second justification, it will be understood that as in the usual machine the second justification lever 46 moves upwardly slightly in advance of the first justification lever 45 whereby the frame 43 is moved upwardly with the spaceband 30 expanding member 42 resting thereon in horizontal position. The upward rise of the first justification lever 45, and with it the brace bar 54, will bring the head 56 of the latter into engagement with one or the other of the projections 35 50, 51 at the completion of the second justification stroke, so that the frame 43 will be pressed upward yieldingly during second justification and during the casting operation while supported by the rod 44 of the second justification lever and 40 the brace bar 54.

It will be seen from the foregoing that the present invention provides means to effect automatic correlation of the incline of the spaceband justification bar and vise jaw toward which 45 spread of the line due to justification of the spacebands is to take place, although it will be understood that the invention comprehends primarily the provision of means for adjusting the justification bar to incline it in the desired direction according to which end of the line is free 50 to move outwardly when the spacebands are expanded, and such means is not necessarily controlled by the devices for selecting the quadding jaw but may be controlled or set independently 55 thereof in order to obtain the above described advantages in the spreading or justification of the matrix lines.

I claim as my invention:—

1. In a typographical machine having movable 60 vise jaws for quadding at either end or centering matrix lines containing expandable spacebands for spreading them, a justifier embodying a spaceband expanding member tilttable in one or the other direction to assist the sliding of the 65 spacebands toward one or the other vise jaw and movable into a horizontal position for expanding spacebands in lines to be centered.

2. A typographical machine according to claim 1, wherein the justifier is operative to effect first 70 and second justification of the lines and comprises a frame portion on which said spaceband expanding member is pivoted, and a laterally adjustable rod operative to bring said member into the appropriately inclined position during 75 the first justification by the justifier.

3. A typographical machine according to claim 1, wherein setting means is provided for quadding with either jaw or centering by both jaws, and the justifier embodies a laterally adjustable rod which is positioned by said setting means and is operative to bring said spaceband expanding member into the appropriately inclined or horizontal position. 80

4. A typographical machine according to claim 1, wherein the justifier is operative to effect first and second justifications of the lines and comprises a frame on which said spaceband expanding member is pivoted, and a laterally adjustable rod operative on said member during first justification to tilt it in one or the other direction and operative on said frame during first justification while said member occupies a horizontal position. 85

5. In a typographical machine having a vise embodying jaws having means for rendering either of them movable to close against one or the other end of a short matrix line containing expandable spacebands, a justifier embodying a spaceband expanding member tilttable into reversely inclined positions according to which end 95 of the line is movable outwardly when the spacebands are expanded. 100

6. In a typographical machine having a vise embodying jaws having means for rendering one or both of them movable to close against one 105 or both ends of short matrix lines containing expandable spacebands, a justifier embodying a spaceband expanding bar pivoted thereon to tilt downwardly toward the movable jaw when one of the jaws is movable or to occupy a horizontal position when both of the jaws are movable. 110

7. In a typographical machine having a vise embodying jaws having means for rendering one or the other thereof movable to close against 115 one or the other end of short matrix lines containing expandable spacebands, and a device for setting said means, a justifier embodying a spaceband expanding member tilttable into reversely inclined positions, and means controlled 120 by said setting device for operating said spaceband expanding member while tilted downwardly toward the movable jaw. 120

8. In a typographical machine having a vise embodying jaws having means for rendering one 125 or both of them movable to close against one or both ends of short matrix lines containing expandable spacebands, and a device for setting said means, a justifier embodying a spaceband expanding member pivoted to occupy an inclined 130 or a horizontal position thereon, and means controlled by said setting device for operating said spaceband expanding member while tilted downwardly toward the movable jaw when one of the jaws is movable and for operating said 135 member while in horizontal position when both jaws are movable.

9. In a typographical machine having a vise embodying jaws having means for rendering either one or both of them movable to close against either 140 or both ends of short matrix lines containing expandable spacebands, and a device for setting said means, a justifier embodying a spaceband expanding bar tilttable into reversely inclined positions and also adapted to occupy a 145 horizontal position, and means controlled by said setting device for advancing said bar on its spaceband expanding stroke while tilted into one or the other of its inclined positions when one or the other of the jaws is rendered movable and for 150

- advancing said bar while in horizontal position when both of said jaws are rendered movable.
10. In a typographical machine, a justifier comprising a justifier bar adjustable into reversely inclined positions, and means for advancing said bar on its justifying stroke while set in one or the other of said inclined positions.
11. A typographical machine according to claim 10, wherein the justifier is operated in two stages, the justifier bar being advanced at one or the other inclined position in the first stage and in horizontal position in the second stage.
12. In a typographical machine having a vise embodying jaws having means for rendering one or the other thereof movable to close against one or the other end of short matrix lines containing expandible spacebands, and a device for setting said means, justifying means for expanding the spacebands embodying a spaceband expanding member tiltable into reversely inclined positions, and means controlled by the jaw setting device for determining the inclined operative position of said spaceband expanding member.
13. In a typographical machine, a justifier comprising a reciprocatory frame, a justifier bar mounted to tilt into reversely inclined positions and to occupy a horizontal position on said frame, and an actuating member engageable with said bar to tilt it into one or the other of said inclined positions and advance it on its justifying stroke and engageable with said frame to advance said bar on its justifying stroke while occupying a horizontal position on said frame.
14. In a typographical machine, a justifier comprising a reciprocatory frame having guide rods rigidly connected thereto, a justifier bar tiltably mounted on said frame to occupy reversely inclined positions and to rest horizontally thereon, said bar having differently located projections thereon, and an actuating member engageable with one or the other of said projections to tilt said bar to incline in one or the other direction and engageable with said frame to actuate it while said bar rests horizontally thereon.
